UNITED STATES PATENT OFFICE.

CARL PHILLIP HERD, OF KEWANEE, ILLINOIS.

MOLD.

1,269,603.

Specification of Letters Patent. Patented June 18, 1918.

Application filed August 28, 1917. Serial No. 188,643.

To all whom it may concern:

Be it known that I, CARL PHILLIP HERD, a citizen of the United States, and a resident of Kewanee, in the county of Henry and State of Illinois, have invented a new and useful Improvement in Molds, of which the following is a specification.

My invention is an improvement in molds, and has for its object to provide a permanent metal mold especially adapted for casting radiator sections.

In the drawings:

Figure 1 is a face view of one section of one embodiment of the invention;

15 Figs. 2 and 3 are sections on the lines 2—2 and 3—3 of Fig. 1, each view looking in the direction of the arrows adjacent the line;

Fig. 4 is a vertical section through another embodiment of the invention;

20 Fig. 5 is a face view of one section of another embodiment of the invention.

In the embodiment of the invention shown in Figs. 1, 2 and 3, the mold consists of two sections, a section 1 and a section 2, which 25 are recessed on their abutting faces to form the outline of the radiator section, as indicated at 3 in Fig. 1. As will be noticed by referring to Fig. 1, the recess is an oblong continuous groove having at its upper end 30 an extension 4, and the groove is continued above the extension to form a gate indicated at 5. Vent openings 6 lead from the top of the recess, and other vent openings 7 lead from the ends of the extensions 4.

35 The core, indicated at 8, which is of sand, as usual, is arranged within the mold, being supported by core prints and chaplets in the usual manner. It will be noticed that the core is vented vertically, as indicated at 9, and lateral vents 10 extend in each direction from the vertical vents to the vent openings 7. The molten metal is poured through a gate 5, and passes down, filling in the space between the core and the mold walls. One 45 of the sections, the section 2 in the present

instance, is provided with an internally extending lug 11 which forms the opening in the lower part of the section for connection with adjacent sections.

In the embodiment of the invention shown 50 in Fig. 4 the improved mold consists of similar blocks 12 which have their adjacent faces recessed, as indicated at 13, to receive thin mold sections 14, the said sections being similar. These sections are recessed to form 55 the external surfaces of the radiator section, and the core 15 is supported within the recesses in the usual manner. The mold has a top opening 16 and lateral vents 17 which communicate with a vertical opening 18 and 60 lateral vents 19, respectively, in the blocks. At the upper end of the blocks is a gate 20 for permitting the metal to be poured into the mold.

In Fig. 5 is shown the section 20^a of a 65 mold designed to cast three different types of radiator sections simultaneously. This section 20^a has recesses 21, 22 and 23 which are shaped to correspond with the external surface of the radiator section to be cast. 70 The section also has a gate 24 and passages 25 and 26 leading from the gate to the tops of the coöperating recesses of the mold section. The extensions 4 of the recesses are to form the bosses of the radiator sections. 75

I claim:

A mold comprising coöperating sections of metal recessed on their inner faces to correspond with the external surface of a radiator section, each recess having a lateral extension at its top for forming a boss on the radiator section at each face thereof and at the top, each extension having a laterally extending vent, the sections having a gate at the top of the mold, and the extensions being 80 of a depth and diameter to receive lateral extensions from the core to support the core in proper position in the mold and out of contact with the bottom of the mold. 85

CARL PHILLIP HERD.
